ABSTRACT

A flow of drying air in the direction of movement of and under successive individual sheets is provided as they leave development means after exposure in a copymaking machine and from which the exposed sheets are received and free liquid removed before the sheets are engaged by the air. The arrangement is such that the sheets are floated to a copy sheet receptacle.

DRYING OF LIQUID DEVELOPED COPY SHEETS IN A COPYING MACHINE

This application is a division of our copending application Ser. No. 665,447, filed Sept. 5, 1967, now U.S. Pat. No. 3,476,479 issued Nov. 4, 1969, which was a division of our application Ser. No. 410,549, filed Nov. 12, 1964, now U.S. Pat. No. 3,345,926, issued Oct. 10, 1967.

The present invention relates to the drying of liquid developed copy sheets in a copying machine, and is more particularly concerned with such drying of copy sheets especially suitable for electrophotographic copying machines employing liquid development of the copy sheets.

Among the objects of the present invention is the provision of new and improved means for drying copy sheets as they are delivered from a liquid development means and in a manner to facilitate movement of the sheets away from the development means to a collection or receiving point.

Another object of the invention is to provide a new and improved method of and means for drying copies after emergence from a liquid toner bath in a copying machine.

A further object of the invention is to provide new and improved means for transporting the finished copy in a copying machine.

Other objects, features and advantages of the invention will be readily apparent from the following description of certain preferred embodiments thereof, taken in conjunction with the accompanying drawings, although variations and modifications may be effected without departing from the spirit and scope of the novel concepts of the disclosure, and in which:

FIG. 1 is a vertical longitudinal sectional elevational schematic view through the front portion of a machine embodying features of the invention;

FIG. 2 is a continuation of FIG. 1 showing the rear portion of the machine;

FIG. 2A is an enlarged fragmentary detail view of that portion of FIG. 2 indicated by the circle II-A;

FIG. 3 is a sectional elevational detail view taken substantially on the line III-III of FIG. 2; and

FIG. 4 is an electrical diagram of the control circuitry of the machine.

An enclosing cabinet 5 houses the machine and includes a base wall 7, a front wall 8, respective opposite sidewalls 9, a rear wall 10 and a top wall 11. Within the housing suitable reinforcing and supporting frame structure is provided including various transverse frame bars 12.

In the front upper portion of the housing 5 are provided means for scanning a document original to be copied. For this purpose, the front wall 8 is inset a short distance adjacent to the top of the cabinet and an upwardly facing receiving ledge 13 is provided on which documents are hand fed into a receiving throat 14 leading to the nip of a driven feed roller 15 and a coacting idler roller 17 by which the document is fed rearwardly through a guide passage between narrowly spaced upper and lower passage plates 18 and 19 which guide the document to the nip of a second driven feed roller 20 and a coacting idler roller 21 set to divert the infed document diagonally downwardly and rearwardly through a passage defined by an upper guide plate 22 and a closely adjacently spaced lower guide plate 23 leading the advancing document into the nip of a driven feed roller 24 and an idler roller 25 set to bend the leading edge of the document to travel about the driven roller 24 as guided by a semicylindrical closely spaced guide bracket 27. Thence, the leading edge of the document passes into the nip of the driven roller 24 and an idler roller 28 by which the document is directed diagonally upwardly and forwardly in reverse to the passage between the plates 22 and 23 and parallel thereto past a scanning aperture 29 defined by a lower document guiding and aperture bracket 30 and an upper spaced document guiding and aperture bracket 31. Cooperative in document guiding relation with the brackets 30 and 31 is a guide and backing plate 32 which extends across the scanning aperture 29 and affords an opaque backing for the document.

Beyond the guide bracket 31, the document is guided into the nip of the driven roller 20 and a cooperating idler roller 33 from which the document is guided into a substantially horizontal plane forwardly by an upper guide plate 34 and a lower guide plate 35 defining a guide passage therewith leading to the nip of the driven roller 15 and a lower idler feed roller 37 by which the copied document is delivered into and through an exit passage 38 defined between spaced upper and lower plates 39 and 40 and located adjacently below the infed or entry ledge 13 in the uppermost front portion of the cabinet.

Illumination of the document as it passes the scanning aperture 29 is effected by means comprising a high-intensity tubular lamp 41 mounted within a channel-shaped parabolic reflector 42 located below the horizontal portions of the document transport system and projecting into the scanning aperture above a reflection path from the aperture to a scanning mirror 43 mounted on one of the cross bars 12 below and forwardly relative to the reflector 42. As indicated schematically by light ray lines L, concentration of scanning illumination of the exposed portion of the document as it passes across the aperture 29 is enhanced by reflecting surfaces provided by respective flanges 44 and 45 on the brackets 30 and 31, respectively.

Light shielding of the scanning area is afforded by the front wall 8, the document guide passage panels 35 and 40 at the top, by respective opposite vertical side panels 47, a rear shielding panel 48 and a bottom shielding panel 49. At its lower end, the front wall 8 is attached to the front cross bar 12 on which the reflecting mirror 43 of the scanning optical system is mounted and which bar is spaced substantially above the bottom wall 7. Attachment of the front end of the bottom shielding panel 49 is also to the front transverse frame bar 12.

Attachment of the upper edge of the rear shielding panel 48 is to the aperture and reflector bracket 30 which, for this purpose, is provided with a longitudinal downwardly and forwardly opening groove 50 alongside the flange 44 and into which the edge portion of the panel 48 is fitted. At its lower end, the panel 48 is attached to the adjacent transverse frame bar 12 which is located in rearwardly spaced relation to the mirror 43 and in upwardly spaced relation to the bottom shielding panel 49.

Between the bottom panel 49 and the overlying spaced frame bar 12 is mounted a lens supporting bracket structure 51 carrying image projecting lens means comprising an assembly including a barrel 52 and aligned for receiving from the scanning mirror 43 the image of the document passing the illuminated scanning aperture 29 and focusing such image generally rearwardly and in this instance slightly upwardly into an exposure aperture 53 located in about the center of the rear portion of the chamber within the cabinet housing 5. Means providing a projection tunnel from the lens or objective assembly 52 to the exposure aperture 53 comprise a rearward extension of the lower panel 49 and an upper tunnel panel 54 having its forward end attached to the transverse frame bar 12 contiguous to the lens assembly.

Supporting the rear ends of the tunnel-forming extension of the lower panel 49 and of the tunnel panel 54 are transverse parallel, coextensive spaced exposure aperture defining bracket members 55 which are desirably constructed identically as the scanning aperture defining and panel supporting bracket 30. The bracket bars 55 have aperture-defining respective flanges 57 and alongside such flanges respective panel-receiving grooves 58 within which the adjacent edge portions of respectively the tunnel-defining panels 49 and 54 are engaged.

A copy sheet magazine including a magazine receptacle 60 is mounted in the housing 5 above the document transport assembly and extending rearwardly under the top wall 11 to a suitable position rearwardly above the projection tunnel and the exposure aperture 53. Access into the copy sheet supply magazine is conveniently through a hinged cover 61 forming part of the top wall. Successive copy sheets are fed from a

stack in the magazine receptacle 60 by frictional feed roller which lies on top of the rear portion of the stack and is carried by one or more arms 63 of a pivotally mounted roller supporting frame pivoted at its rear end portion on a horizontal axis pivot 64. This feed roller is driven by an electrical motor 65 mounted under the rear portion of the top wall 11, alongside the right-hand inner housing vertical frame panel 47 and has a drive shaft 67 coupled with the feed roller by a drive pulley 68 on the shaft with a flexible driving element belt 69 trained thereover and over a similar driving pulley (not shown) carried corotatively by one end portion of the shaft carrying the roller 62 and by which the feed roller is driven counterclockwise as viewed in FIG. 2. Adjustable side gripping means 70 engage the sides of the stack of sheets in the magazine and resist feeding of multiple sheets.

From the magazine 60, each of the copy sheets 59 is directed into a converging guide throat 71 extending rearwardly and then downwardly to guide the feed copy sheet into a plane past the exposure aperture 53. At the lower end of the guide throat the copy sheet is directed to the nip of a driven feed roller 72 and a coacting idler roller 73 which then assume onward feeding transportation of the copy sheet.

For electrophotographic copying, the copy sheets 59 are of the electrophotographic type such as a paper backing having a photosensitive coating comprising zinc oxide or the like plus a binder. Such material is adapted to take an electrostatic charge on passing through a charging device 74 including corona discharge wires 75 located alongside and across the path of travel of the copy sheet, and preferably on both sides of such path. This corona charging device 74 is located as close as practicable to the downstream side of the feed rollers 72, 73 and adjacent to the upstream side of a set of feed rollers comprising a driven roller 77 and a coacting idler roller 78 to the dielectric nip of which the charged copy sheet is fed from the charging device. Immediately following the feed rollers 78 and 77, the charged copy sheet passes the exposure aperture 53 with the sensitized surface of the sheet exposed to the image projected from the scanned document concurrently passing the scanning aperture 29. Backing the copy sheet across the aperture 53 is a plate 79 cooperating in appropriately spaced relation with the aperture-defining brackets 55 to provide a passage and guide for the sheet. Immediately on leaving the exposure aperture guide passage, the exposed sheet is engaged by a set of dielectric transport rollers comprising a driven roller 80 and a coacting idler roller 81.

Immediately on leaving the transport roller 80 and 81, the exposed sheet is transported through image developing and fixing means comprising a receptacle 82 in the form of a troughlike tray opening upwardly and having an elevated rear curved lead-in edge 83 adjacent to the discharge side of the rollers 80 and 81. Within the developer tray 82, the copy paper is guided in an arcuate path downwardly and forwardly and then generally upwardly and forwardly and passes through a developer bath 84 comprising a suitable liquid vehicle and toner or developer particles. This developer bath or solution is maintained in constant circulation from a supply tank 85 below the tray 82 and from the bottom of which the solution is pumped by a pump unit 87 through a riser duct 88 into the bottom of the tray and returns through an overflow duct 89 leading from the tray into the tank. Driving of the pump unit 87 is by a pump motor 90 which may be conveniently mounted above a top cover 91 for the tank 85 on posts 92 and has a drive shaft 93 extending down into driving relation with the pump unit 87.

On leaving the toner bath 84, the developed copy sheet is directed by the curved guide wall of the tray 82 into the nip of transport and squeeze rollers comprising a driven roller 94 and a coacting idler roller 95 by which the surplus solution is squeezed from the copy sheet and the sheet is transported away from the developer tray. Solution squeezed from the sheet is received in a drip trough 97 under the roller 94 and comprising a forward extension on the tray 82. A drain duct 98 returns collected solution from the trough 97 into the tank

85. Access to the developer tank and tray assembly may be had through the backwall 10 of the housing through a removable panel or door 99.

On leaving the squeezing and transport rollers 94, 95 the still damp and now fully developed copy sheet is propelled generally forwardly and is deflected downwardly and forwardly by the overlying tunnel extension of the shield 49 which is desirably provided with longitudinal downwardly projecting spacer ribs 100 to avoid possible adherence of the damp copy sheet thereto. Underlying the path of movement of the copy sheet is discharged from the rollers 94 and 95 is a downwardly and forwardly extending guide plate 101 providing a discharge chute leading to a receiving area in the lower forward portion of the housing between the bottom wall 7 and the top side of the chute provided by the downwardly facing wall of the light tunnel, herein the shield panel 49, and readily accessible at the front of the machine below the mirror 43 for removal of the finished copies.

Means are provided for accelerating movement of the discharged copy sheets down the ramp into the receiving hopper and for simultaneously drying the damp sheets. In a highly desirable manner, this is effected by providing an air cushion under the sheets as they travel down the chute or ramp 101 whereby to effect an antifriction air layer under the sheets to float the sheets into the receiving hopper. For accelerating drying of the sheet such air is desirably heated. Economically, the source of waste heat created by the scanning lamp 41 is utilized for the purpose. Therefore, an air circulation suction port 102 is provided in one of the vertical frame panels 47, herein the one located at the left side of the cabinet adjacent to the reflector trough and of a size to pass a substantial volume of air therethrough from the scanning chamber. Leading from the suction port 102 downwardly and rearwardly between the frame panel 47 and the adjacent sidewall 9 is a suction duct 103 extending downwardly and rearwardly and communicating with a horizontal suction tube 104 which opens into the intake of a rotary squirrel cage blower 105 located to discharge toward louvers 107 opening through the lower end portion of the chute plate 101 and through a vertical downward partition extension 108 of the chute plate defining the rear of the receiving hopper area. Through this arrangement, cooling air is circulated through the scanning chamber and over and past the lamp 41 and the reflector 42 as a result of suction developed by the blower 105 and the heated air is blown through the louvers 107 to provide the discharged copy sheet propelling and drying air movement and indicated by the directional arrows in FIG. 2A. After the trailing edge of the copy sheet passes beyond the lower end of the chute plate 101, air blown through the louvers 107 in the plate 101 as well as the air issuing through the louvers 107 in the vertical partition 108 acts on the upper side of the sheet to force it downwardly onto a receiving plate 109. It will be observed that the series of louvers 107 terminates a substantial distance above the innermost end of the receiving plate 109 so that as the rear end of the copy sheet drops below the series of louvers, press-down action of the air pushing through the louvers accelerates piling of the sheet toward the receiving plate. To facilitate removal of copy sheets from the discharge receptacle, a retractable plate structure 110 may be provided.

Driving of the blower 105 as well as all of the several document original and copy sheet transport rollers is effected by a single electrical motor 111 having a drive shaft 112 extending therethrough and on one end portion of which the blower 105 is directly corotatively mounted. The opposite end portion of the shaft 112 is suitably coupled with a suitable speed reducing gear unit 113 supporting the motor and carried by the adjacent side vertical frame panel 47. A drive shaft 114 of the reduction gear unit carries corotatively a driving wheel which may comprise a sprocket 115 over which is trained a flexible driving coupling member comprising a chain 117 running drivingly over respective sprocket gears on the several driven transport rollers. At a suitable point, as in the span of the drive chain 117 between the driven rollers 24 and 72, a slack takeup

idler 118 is desirably provided. Through this arrangement, all of the driven rollers travel at the same speed in both the document original transport system and the copy sheet transport system.

An electrical circuit is provided (FIG. 4) for controlling operation of the machine. For this purpose, the circuit includes customary power leads 119 adapted to be connected with a suitable source of electrical current. Directly connected in this circuit are the pump motor 90 and the blower and chain drive motor 111, so that when a master control switch 120 is closed the document and copy sheet transport systems and the blower 105 run continuously and the liquid toner 84 is in constant circulation for optimum toner distribution throughout the liquid vehicle and for continuous replenishment of the toner supply in the development tray. Conveniently the master switch 120 is mounted on the front of the cabinet (FIG. 1) for suitable "on" and "off" manipulation.

Operation of the copy sheet feed drive motor 65 is under control of the document to be copied and of the successive copy sheets and the copy sheets control operation of the lamp 41 and the charging device 74. For this purpose, the lamp 41, the feed motor 65 and a power pack 121 for the corona discharge device are connected in the electrical power supply circuit under the control of various trip or micro switches including a normally open switch 122 which is mounted on or adjacent to the document guide plate 22 between the document transport rollers 21 and 25 and has a trip arm 123 disposed in the path of the in-travelling document when it enters the flow or guide path between the plates 22 and 23. Tripping of the actuator 123 by the document, closes the switch 122 and thereby closes the energizing circuit through the feed motor 65 whereby one of the copy sheets 59 is fed into the copy sheet transport system and actuates a two-way control switch 124 (FIGS. 2 and 4) having a trip arm 125 disposed in the path of the copy sheet between the transport rollers 72, 73 and the corona charging device 74. This breaks the circuit through the feed motor 65 and closes a circuit to energize a relay 127 closing normally open switch contacts 128 and completing an energizing circuit through the lamp 41 and the corona discharge power pack 121. The switch 124 remains under the control of the copy sheet until the trailing end of the copy sheet leaves the transport rollers 80 and 81, by provision of a second actuator 129 extending into the path of the sheet on the exit side of the transport rollers 80 and 81 and just above the lead-in lip 83 of the developer tray.

Promptly upon release of the switch actuator 129 from the charged copy sheet, the switch 124 automatically returns to its feed motor circuit closing condition and the feed motor 65 is energized to feed the next succeeding copy sheet from the magazine into the guide throat 71. At the exit from the guide throat and immediately before the copy sheet transport rollers 72 and 73 a trip arm or actuator 130 of a normally closed switch 131 is tripped by the leading edge of the newly fed copy sheet and opens the switch 131 to open the feed motor circuit and deactivate this motor until the shunt around the switch 131 is again closed by closing of the control switch 122 by a document to be copied. For synchronization the distance from the tripping position of the trip arm 123 of the switch 122 to the near side of the scanning aperture 29 in the path of travel of the document is identical with the distance from the engagement position of the trip arm 130 of the control switch 131 and the near edge of the exposure aperture 53. Thereby, automatic synchronization of documents to be copied and corresponding copy sheets is attained for high-speed operation. In practice virtually as soon as a document to be copied is returned through the exit 38, the finished copy is delivered into the receiving hopper in the lower front of the machine and in a sufficiently dry condition to be handled immediately.

An illumination intensity modulating shutter 132 is pivotally mounted adjacent to the scanning mirror 43 and is operable from the front of the machine by a lever 133.

We claim:

1. An arrangement for handling light-sensitive copy sheets which have been exposed to light to provide a latent image thereon, comprising:

a receptacle for liquid developer solution;
means for transporting the sheets through the developer solution and then moving the developed sheets onward while still damp towards a receiving point with one face generally downward;
means for providing drying air under and toward the downward faces of the damp sheets as they move from the receptacle to the receiving point and in sufficient volume to substantially dry the sheets for immediate handling upon arrival at the receiving point; and
means for directing air downwardly against the sheets after they have reached the receiving point.

2. An arrangement according to claim 1, said means for directing air downwardly comprising a series of downwardly directed louvers disposed at a height such that the downwardly directed air strikes the trailing end portions of the sheets as they pass thereby.

3. In a machine for making copies and including means for exposure of a copy sheet:

means for liquid development of the exposed copy sheet;
means receptive of the exposed copy sheet from the liquid and operative to remove free liquid from the copy sheet;
upwardly facing downwardly sloping guide means defining a space thereunder and having openings and along which the sheet moves from said free-liquid-removing means with one face of the sheet confronting the guide means while moving therealong; and means mounted in said space under said guide means and operative to effect a flow of drying and propelling air through said guide means under the sheet and against said one face.

4. A machine according to claim 3, including a lamp in said exposure means, and a duct leading from the vicinity of said lamp and conducting air heated by the lamp to said means mounted under said guide means.

5. A machine according to claim 3, in which said guide means comprises a perforated plate having (a surface extending obliquely downwardly and facing generally away from the free-liquid-removing means and having) a plurality of air openings directed (generally away from the removing means so that the drying air is also directed generally away from the removing means) to float the sheets along said plate (surface and away from said removing means).

6. An arrangement for handling light-sensitive copy sheets which have been exposed to light to provide a latent image thereon, comprising:

a receptacle for liquid developer solution;
means for transporting the sheets through the developer solution and then moving the developed sheets onward while still damp towards a receiving point with one face generally downward;
a perforated guide plate having a space thereunder and providing a ramp sloping downwardly and away from said receptacle toward said receiving point; and
means in said space under said plate for driving drying air toward and to issue through said plate and impinge the downward faces of the damp sheets as they move from the receptacle to the receiving point along the plate.

7. An arrangement according to claim 6, in which said means for driving drying air comprises a blower mounted under the plate and operative to drive the air therethrough.

8. An arrangement according to claim 7, including a motor for driving said blower and said transport means.

9. In a machine for making copies and including means for exposure of a copy sheet:

means for development of the exposed copy sheet;
means for guiding the developed copy sheet to a receiving point; and
means for directing air downwardly against the trailing end portion of said sheet to enhance stacking of the sheet at said receiving point.

10. In a machine according to claim 9, a vertical plate portion over which the sheet is advanced to said receiving point, and generally downwardly directed louvers in said plate portion through which the air is directed.

11. In a machine for making copies and including means for exposure of a copy sheet;

means for liquid development of the exposed copy sheet; squeeze rollers operative to remove free liquid from the copy sheet as it leaves the liquid development means and impelling the sheet toward a receiving point;

means defining a guideway flaring from said rollers generally downwardly and toward the discharge point;

means for driving air through said guideway means onto a

face of the sheet as it moves through the guideway; said guideway including a perforated plate and said means for driving air driving the air through the perforated plate; said plate having louvers biased in the direction of movement of the sheet; said plate including a downwardly extending portion at an end thereof remote from said rollers; and said downwardly extending portion having generally downwardly directed louvers for directing air against trailing end of the sheet after it leaves said plate.

12. In a machine according to claim 11, an air blower under said plate and driving the air through said louvers.
